CLAIM

The ornamental design for a lawn mower blade, as shown and described.

DESCRIPTION

FIG. 1 is a perspective view of a lawn mower blade in accordance with the present invention;

FIG. 2 is a second perspective view of the lawn mower blade of FIG. 1;

FIG. 3 is a bottom view of the lawn mower blade of FIG. 1; FIG. 4 is a top view of the lawn mower blade of FIG. 1; FIG. 5 is a left side view of the lawn mower blade of FIG. 1;

FIG. 6 is a right side view of the lawn mower blade of FIG. 1;

FIG. 7 is a rear view of the lawn mower blade of FIG. 1; and, FIG. 8 is a front view of the lawn mower blade of FIG. 1. The broken lines of FIGS. 1-8 illustrate portions of the lawn mower blade that form no part of the claimed design.

1 Claim, 7 Drawing Sheets
